UNITED STATES PATENT OFFICE.

FRANCES RAE BAER, OF KANSAS CITY, MISSOURI.

GAME.

Application filed February 5, 1926. Serial No. 86,191.

My invention relates to games and more particularly to one relating to cartomancy, the principal object of the invention being to provide a device for employing that art as a game wherein card reading is effected by mechanical selection.

In accomplishing this object I have provided improved details of structure, the preferred forms of which are illustrated in the accompanying drawings wherein:—

Fig. 1 is a plan view of a game device constructed in accordance with my invention.

Fig. 2 is a cross sectional view through the device on the line 2—2 of Fig. 1.

Referring more in detail to the drawings, 1 designates a card or board upon the various oracles involved in the play, decorative matter (not shown) and indicia pertaining to the game may be printed to form the field, the functional indicia comprising a ring 2 divided into spaces 3 by radial lines 4 extending from the center to the periphery of the circle. Printed in each space 3, near the periphery of the circle, is a facsimile of one of the playing cards of an ordinary deck, there being one space for each card, the cards of the several suits being grouped together and arranged in order, each suit occupying a quarter of the circle, the quadrants being separated along horizontal and vertical lines. For example, the first quadrant, 5, contains the suit of hearts, the second quadrant, 6, the suit of spades, the third quadrant, 7, the suit of diamonds, and the fourth quadrant, 8, the suit of clubs.

In an inner ring 9 adjacent the ring 2 and between the radial lines separating the card spaces 3 are imprinted the numerical values of the corresponding cards.

Pivotaly mounted on the field at the center of the circle is a pointer or indicating device 11, preferably comprising a flat strip of sheet metal or cardboard, having a point 45 12 at one end and a corresponding notch 13 at the other end to represent an arrow and balance the pointer on its pivot. The pivot 14 comprises a rivet which extends through an opening 15 midway of the pointer, through a spacing washer 16 and through an opening 17 in the board 1, so that the arrow may rotate freely upon its pivot, out of contact with the board.

At each corner of the field, outside of the circle is a schedule 18, 19, 20 or 21 headed by the title of a suit, the hearts, clubs, spades

or diamonds, and comprising a list of the cards in their order, each number or initial being followed by a description of the oracle meaning or translation of the card, and each schedule topped by the word "Yes" or "No" to indicate certain results of the play hereinafter described; in the present arrangement, the word "Yes" appearing above the upper left and lower right schedules and the word "No" above the lower left and upper right schedules. At the bottom of the field is a special schedule relating only to face cards and consisting of the letters "A," "K," "Q" and "J" to designate the ace, king, 70 queen and jack, followed by the oracle meaning and preceded by the figure "3" for a purpose presently described.

While many different methods of play may be employed with the device, I will describe one which I have devised and recommended in instructions accompanying the game.

In playing the game, the suits indicate 80 complexions in so far as the readings relate to persons, diamonds indicating decided blondes; hearts, medium blondes; clubs, medium brunettes; and spades, decided brunettes. The player makes a wish, as for instance, that he may be successful in a business matter then of interest to him. He then spins the pointer to the right three separate times, making note of the card to which the arrow points when at rest after each spin. Assuming that these stops are at the ten of diamonds, the six of hearts and the five of clubs, the player will consult the schedules and note that the ten of diamonds means "Large amount of money received or valuable present;" the six of hearts, "Friend" 95 and the five of clubs, "Package or business papers." The player again spins the pointer three times, noting the cards at which the pointer stops, as before, and again consults the schedule for translation. This time he 100 may have the seven of spades, meaning "From away;" the ace of clubs, meaning "A business transaction" and the jack of diamonds, meaning "A light young man." He then combines the six readings to complete 105 the message, which, in the example given, can be connected to read: "The inquirer will receive some papers from a light young man friend who is out of town. These papers are with reference to a business transaction involving a large amount of money."

The player may make as many spins as

he desires, taking note of the cards at which the pointer stops, consulting the schedules to obtain the meanings of the cards and finally connecting the meanings as a message in answer to the question that he has asked.

Next, the game may be extended by the player making three spins to determine whether his wish will come true. On the first three spins he may get the ten of hearts, meaning "Good luck"; five of diamonds, meaning "Real soon"; and the five of hearts, meaning "Contract or promise"; which, when assembled, may read: "Real soon there will be good luck concerning a contract."

He may then spin three times to determine the result of the contract, and may get the nine of clubs meaning "Sure", the ten of diamonds, meaning "Large amount of money" and the king of hearts, meaning "The inquirer", which three meanings, connected, make up the message "Real sure there is a large amount of money to the inquirer concerning his wish."

The player may then desire to know how long it will be before his wish will come true. For his answer he again spins the pointer and if it stops at "3", he is informed that his wish will come true within three months, the number of the card in this instance representing months.

Should the player desire a "yes" or "no" answer to his question, he spins the pointer and his answer is determined by the corner word in the quadrant in which the point of the arrow comes to rest.

If, during the play, the pointer should stop three times at the ace, king, queen or jack of the player's complexion suit, he refers to the special schedule for the additional reading there indicated.

From the foregoing it is apparent that the game may be played by one or more; that it is capable of various modifications and adaptations according to rule or whim of the players and, involving the art of cartomancy in addition to mere amusement, affords a greater range of interest than an ordinary game.

What I claim and desire to secure by Letters-Patent is:—

1. In a game of the character described, a field bearing an annular series of card groups, each including representations of the cards of a suit, and bearing a separate schedule for each of the groups including identifying and oracle meaning designations of the several cards of the suit, and a pointer pivotally mounted concentrically of the series.

2. In a game of the character described, a field bearing an annular series of card groups, each including representations of the cards of a suit and bearing a separate schedule for each of the groups including identifying and oracle meaning designations of the several cards of the suit, each schedule including a general designation common to all cards of the group, and a pointer pivotally mounted concentrically of the series.

3. In a game of the character described, a field bearing an annular series of card groups, each including representations of the cards of a suit and bearing a separate schedule for each of the groups including identifying and oracle meaning designations of the several cards of the suit and bearing an additional schedule including value and oracle meaning designations of a selected number of cards common to all of the suits, and a pointer pivotally mounted concentrically of the series.

4. In a game of the character described, a field bearing an annular ring divided radially to form separate spaces, indicia in said spaces representative of the cards of a deck, the indicia arranged in suit groups, a schedule for each of the groups including identifying and oracle meaning designations for the several cards of that group, and a pointer pivotally mounted concentrically of said ring.

5. In a game of the character described, a field bearing inner and outer rings divided radially to form separate spaces, indicia in the spaces of the outer ring representative of the cards of a deck and arranged in suit groups, indicia in the spaces of the inner ring representative of the value of the cards represented in corresponding spaces of the outer ring, a schedule for each of the groups including identifying and oracle meaning designations for the several cards of that group, and a pointer pivotally mounted concentrically of said ring.

6. In a game of the character described, a field comprising an annular ring divided into radial spaces, a series of indicia representative of cards of a deck divided into suit groups, each group occupying a quadrant of the field divided along horizontal and perpendicular lines, a schedule for each group including identifying and oracle meaning designations for the several cards of that group, and a pointer pivotally mounted concentrically of said ring.

In testimony whereof I affix my signature.

FRANCES RAE BAER.
